UNITED STATES PATENT OFFICE.

ERNEST F. FARRELL, OF ST. LOUIS, MISSOURI.

LACE-CURTAIN, DRAPERY, AND SHADE SUPPORT.

1,186,979.

Specification of Letters Patent. Patented June 13, 1916.

Application filed February 25, 1916. Serial No. 80,424.

To all whom it may concern:

Be it known that I, ERNEST F. FARRELL, a citizen of the United States, residing at St. Louis, State of Missouri, have invented 5 certain new and useful Improvements in Lace-Curtain, Drapery, and Shade Supports, of which the following is a full, clear, and exact description, reference being had to the accompanying drawings, forming a 10 part hereof.

My invention has relation to improvements in lace curtain and shade supports; and it consists in the novel features of construction more fully set forth in the specification and pointed out in the claims.

The object of my invention is to provide a support for lace curtains, draperies and shades in a single structure, the whole being capable of being so mounted on the 20 window frame as to afford access to the windows at any time.

A further object is to provide a support which may be removed or placed back on the window frame without the necessity of a 25 step-ladder; one which may be installed on either side of a window frame; one which may be readily manipulated, and one possessing further and other advantages 30 better apparent from the following detailed description in connection with the accompanying drawings in which—

Figure 1 represents an inside elevation of a window and its frame broken at the middle showing my invention applied there- 35 to and in normal position; Fig. 2 is a side elevation of Fig. 1; Fig. 3 is a view similar to Fig. 1 with lace curtain and drapery swung outwardly to expose the window; Fig. 4 is a top plan of the device broken 40 in the middle with parts in normal position; Fig. 5 is a vertical section on the line 5—5 of Fig. 4; Fig. 6 is an elevation of Fig. 4 45 (broken in the middle); Fig. 7 is an end view of Fig. 4 looking toward the left; and Fig. 8 is a vertical sectional detail on the line 8—8 of Fig. 4.

Referring to the drawings, F, represents a conventional window frame and S, S', the lower and upper window sashes as well un- 50 derstood in the art. Secured to one side of the frame at a convenient point is a plate 1 provided with a bracket or stem 2 the outer terminal of which is screw-threaded. Over the screw-threaded end of the stem is 55 passed a socket 3 which can be carefully adjusted to bring its axis into a vertical

plane, the socket being clamped in its ad- justed position by a lock-nut 4 mounted on the threaded portion of the stem 2. The socket or hollow bearing 3 is adapted to 60 receive a sleeve or hollow spindle 5 which terminates at its upper end in a head 6 adapted to rest against or engage the upper end of the socket, the head 6 being provided with a diametrically disposed groove or re- 65 cess a. Obviously, the spindle 5 may be ro- tatably adjusted in its socket 3 so as to bring the longitudinal axis of the groove a at right angles to the plane of the window frame or of the wall carrying said frame, 70 the spindle after adjustment being set-screwed in position by a screw 7 operating through the wall of the socket 3.

Insertible through the bore of the sleeve or spindle 5 is a stem 8 said stem being car- 75 ried by or secured to, the head or polygonal terminal 9 of an arm or bracket 10, the cross-section of the head 9 being such as to be received by the depression or groove a when the stem 8 is inserted into the sleeve 80 5. In this way the bracket 10 becomes coupled to the grooved head 6, and since the axis of the groove is carefully adjusted at right angles to the window frame it fol- 85 lows that the bracket 10 will project in a 85 true perpendicular to said frame. To prevent accidental upward displacement of the bracket 10 when once locked to the head 6, I mount a flexed spring 11 on the set screw 7 as shown, and when the screw is driven 90 home to hold the sleeve 5 against rotation, it at the same time forces the lower free end of the spring against, and causes it to bite 95 into, the projecting portion of the stem 8, thus preventing withdrawal of the stem and consequent lifting of the head 9 out of its groove a.

Passed over the bracket 10 and set-screwed thereto by a screw 12 near the base of the head 9 is the enlarged terminal 13 of a rod or bar 14, which is held rigidly to the bracket 10 in a horizontal position, said rod being provided with adjustable depending brackets 15, 15, between which may be sup- 100 ported the roller R of the conventional roller shade C well understood in the art. The brackets may be clamped to the rod 14 in their adjusted position by screws 16. The member 14 may be termed as the shade sup- 105 porting rod or bracket, the base 13 thereof being provided with a depending screw-stem 110 17 for a purpose to presently appear. The

outer end of the stem or bracket 10 is screw-threaded, said end having coupled thereto the upper terminal head 18 of a depending tube or bearing 19 the bore of which is traversed by the terminal vertical spindle or stem 20 of a horizontal arm or rod 21 the base of which (that is, the portion adjacent its juncture with the spindle 20) is receivable in a diametrically disposed groove or recess α' in the head 18, which in practice is adjusted to bring the longitudinal axis of the recess at right angles to the stem 10, or parallel to the plane of the window. When once adjusted, the head 18 is clamped in position by a lock-nut 22 on the threaded portion of the stem 10. Formed integrally with and bent from the rod 21 is the diagonal brace 21' whose free end is perforated to pass over the lower screw-threaded projecting terminal of the spindle 20, a lock nut 23 securing the parts in place. The member 21 serves as a lace-curtain support. Secured to the member 21 by means of any conventional form of clamps or straps 24 (not necessary to describe in detail) is a drapery-supporting rod 25, the same being disposed parallel to the member 21 and spaced properly therefrom. Since the free end of the shade supporting rod 14 is not braced as is the member 21, I provide a support therefor by means of a bracket 26 fastened to the window frame at the proper point to serve its purpose.

It was stated above that the bite of the spring 11 against the stem 8 prevents accidental upward displacement of said stem and consequent dislodgment of the head 9 of the bracket 10 out of its groove α . The friction between the parts 8 and 11 is not sufficient to prevent lifting of the stem 8 out of its sleeve 5 if sufficient force be applied. Accordingly, and to avoid the necessity of a step-ladder when occasion arises to take down the support, I provide a stick or handle H, with a terminal interiorly screw-threaded socket which I screw over the screw-stem 17 depending from the base 13 of the shade-supporting rod, and then by sufficient force exerted in an upward direction I can lift the pin or stem 8 out of its sleeve 5, and the head 9 out of its groove α and thus lift and remove the entire fixture (with the exception of the bracket 2 with its socket 3, sleeve 5 and spring 11) from its mounting (dotted showing Fig. 7) permitting the ready removal of soiled curtains, shades and draperies and the placing of corresponding clean ones on the fixture. To replace the fixture the operator drops the stem 8 back into its sleeve 5, taking care that the head 9 of the bracket 10 reenters the groove α of the sleeve-head 6.

Should access to the windows be at any time desired, the portion of the fixture carrying the lace curtain L and drapery D

may be swung out of the way in the following manner: The operator can readily screw the stick H to the lower screw-threaded terminal of the spindle 20 (Fig. 6) and lift said spindle sufficiently to raise the rod 21 out of its groove α' in the head 18, thus leaving the spindle (with its rods 21 and 25) free to be swung outwardly one hundred and eighty degrees, when upon lowering the spindle, the rod 21 will re-engage the groove α' leaving the swinging portion of the fixture with its lace curtain and draperies opened outward against the wall on either side of the window frame, thus leaving the windows accessible for washing, cleaning or any other purpose. The parts may be swung back into position as clearly obvious from the drawings. The stick H when not in use is kept out of sight or in any convenient and handy place.

It is clear from the foregoing that the socket 3, sleeve 5, head 18 and the manner of assembling of the parts with which these members are identified, allow for all necessary vertical and horizontal adjustments to cause an even hanging of the shades, curtains, and draperies. I may of course depart in a measure from the details herein without affecting the nature or spirit of my invention.

Having described my invention what I claim is:

1. In a fixture of the character described, a suitable supporting member, a vertically rotatable socket carried thereby, a horizontally rotatable member mounted in the socket, an arm leading from said member and detachable therefrom, a tubular member at the outer end of said arm, an oscillating curtain-supporting arm provided with a spindle mounted rotatably in said tubular member, and means on the tubular member for locking the curtain-supporting arm against movement when swung opposite to, or away from the window.

2. In a fixture of the character described, a member supported at a fixed point and adjustable in horizontal and vertical planes about said point of support, a horizontally oscillating curtain-supporting arm leading from said member at a point removed from the point of support of the member, said arm being free to be moved bodily in a vertical direction, and means adjacent the axis of oscillation of the arm for locking said arm when in its lowest position and permitting free oscillation thereof when raised a suitable distance from its locked position.

3. In a fixture of the character described, a bracket secured to the side of a window frame, a vertically rotatable socket at the free end of said bracket, a horizontally rotatable sleeve mounted in the socket, an enlarged head on the sleeve engaging the upper end of the socket and provided with

a diametrically disposed groove or recess, an arm having one end engaging said recess and provided with a stem passed through the bore of the rotatable sleeve, independent 5 means for locking the socket and sleeve respectively in their adjusted positions, a shade-supporting rod set-screwed to the arm adjacent the terminal engaging the recess aforesaid, the opposite end of the arm being 10 screw-threaded, a tubular bearing terminating at its upper end in a diametrically grooved or recessed head secured to said screw-threaded end of the arm aforesaid, a horizontally swinging curtain-supporting 15 rod adapted to engage the groove of the last mentioned head and provided with a vertical spindle loosely traversing the bore of the tubular bearing, and having a lower screw-threaded terminal projecting beyond the 20 bearing, a diagonal brace member leading from the spindle at a point below the tubular bearing to the outer end of the rod, a drapery rod secured to the curtain-support-

ing rod, the arm engaging the recess of the rotatable sleeve and its stem aforesaid being 25 liftable out of the sleeve and recess, and the swinging curtain-supporting rod being liftable out of the recess of the terminal head of the tubular bearing supporting the spindle 30 of said rod.

4. In a fixture of the character described, a suitable supporting member, a vertically rotatable socket carried thereby, a horizontally rotatable member in said socket, an arm leading outwardly from said member 35 and detachable therefrom, and a horizontally oscillating curtain-supporting arm mounted at the outer free end of the first mentioned arm.

In testimony whereof I affix my signature, 40 in presence of two witnesses.

ERNEST F. FARRELL.
